UNITED STATES PATENT OFFICE

JOHANN G. KOENIGSBERGER, OF FREIBURG, GERMANY

METHOD OF LOCATING SALT OR ROCK LAYERS

Application filed January 5, 1923, Serial No. 610,898, and in Germany January 2, 1922.

My invention refers to a method of locating the situation and form of salt deposits, gravel and rock layers and the like.

It has been proposed by Mintrop to use 5 for this purpose long elastic waves and concussions caused artificially by aid of explosives, such waves being observed in a special instrument called "seismograph" and permitting to ascertain the nature of the subsoil.

10 On the other hand Fessenden has indicated a method for locating ore bodies by inflection of short acoustic waves, such inflection meaning refraction and reflection.

The present invention, being also based on 15 the use of acoustic waves and electro-acoustic apparatus to record these waves, makes use of the modern sound-detecting apparatus, with or without amplifier tubes connected with oscillograph tubes or other recording devices, or without such the novel object as regards the use of acoustic waves being the locating of salt deposits, of the extension of the boundaries of layers of gravel and the like. Owing to the fact that the sound-detecting 20 devices are considerably cheaper and also more easily portable than seismographs for earthquake waves, the novel method permits of employing sound-detecting devices in various points at a time, and, therefore, to use 25 a method differing from the one used with 30 earthquake waves.

With or without conducting wires comparative observations can be made, and if necessary, recorded at a single point only. The 35 time of the arrival of the waves, or of certain distinct marks in the trains of the waves may then be compared with each other and with the time at which the sound was produced, and also the intensity of the waves at the various 40 points may be measured and compared.

In order to make my invention more clear, I refer to the accompanying drawing in which are shown diagrammatically by way of example three different vertical sections 45 through portions of the soil and of the subsoil.

Figure 1 represents a section of a deposit of gravel embedded in solid rock.

50 Figure 2 is a section of a salt deposit.

Figure 3 illustrates a third modification.

Referring to Figure 1, 4 is the deposit of gravel, and 5 is solid rock having the gravel embedded into it. The source of sound is placed at the point 1, and sound detecting devices at the points 2 3 6 7. All these points 55 1 2 3 6 7 are connected electrically with a recording apparatus either by aid of a wire, or in the wireless way. Amplifiers may be inserted in these connections. The sound produced at the point 1 is intensified and 60 weakened in certain different intervals of time, the intensity curve being thus characterized by different gaps and projections which are differently spaced as regards time. An 65 intensity curve like that produced at the point 1 is received at the points 2 3 6 7, but at different absolute times. The curve is received in the sound-detecting apparatus 2 3 6 7 and is electrically conducted to a recording device located at the point 8. The intensity curves 70 thus electrically transmitted to the recording apparatus 8 are directly observed and measured, for instance, with the aid of a rotary mirror. The relative displacements of the 75 times of said intensity curves may be compared by optical length measurements if the number of rotations of the mirror is known, or the electromagnetic effect is recorded with the aid of a galvanometer. Either way permits of drawing conclusions as to the length 80 of the various ways, for instance from the point 1 over the points 2 and 3 to the point 6, and from the point 1 around the gravel 4 in the medium 5 to the point 6. The difference 85 of time which the sound requires to get from the point 2 to the point 3 shows the velocity of the sound along the gravel 4. In the same manner the differences of time at the points 6 and 7 for the direct way across the gravel 4 shows the velocity of the sound along the 90 medium 5. From the differences of time for the two paths of sound which lead to the point 6, and with the aid of the data previously obtained, the length of the unknown boundary line located in the depth between the deposit of gravel 4 and the rock 5 may be 95 determined.

A similar procedure is adapted in ascertaining the location of a layer of salt (Figure 2). The source of sound is placed at the 100

point 1. Sound detecting apparatus are placed at the points 2 and 3. Also in this case the difference in the time of arrival of the same projection of the intensity curve 5 between the points 1, 2 and 3 is observed whereby the velocity of travel of the sound through the soil 4 is obtained. Besides sound waves are reflected at the boundary surface between the layer of salt 5 and the 10 soil 4, and these waves arrive at the point 3 later than the waves travelling directly from the point 1 to the point 3 and being propagated immediately below the surface of the soil. This permits of drawing conclusions 15 regarding the length of the way and, consequently, the depth in which the salt deposit is to be found.

In the third example (Figure 3), the source of sound is placed at 1; the sound-detecting apparatus at 2 and the recording apparatus at 8. At the point 2 there is received the wave propagated directly below the surface of the soil, as well as the wave reflected by the deposit 5 and arriving at 2 correspondingly later. The difference of time indicates the way of the reflected wave and, thus, the depth in which the deposit commences, whereas the speed of the sound travelling through the soil 4 is determined by the difference of time between the waves ascertained 30 at the points 1 and 2.

I wish it to be understood that I do not desire to be limited to the exact details of procedure and construction herebefore described, as many obvious modifications will occur to a person skilled in the art.

I claim:

1. The method of ascertaining the position and nature of a mineral deposit embedded in 40 the soil comprising producing acoustic waves at a point near said deposit varying at intervals the intensity of such waves, receiving at another point the direct acoustic waves travelling from said first point to said second 45 point and also the acoustic waves reflected from said deposit and electrically recording both said kinds of waves.

2. The method of ascertaining the position and nature of a mineral deposit embedded 50 in the soil comprising producing acoustic waves at a point near said deposit varying at intervals the intensity of such waves, receiving at another point the direct acoustic waves travelling from said first point to said second 55 point and also the acoustic waves reflected from said deposit, converting said acoustic waves into electric oscillations and recording same.

3. The method of ascertaining the position 60 and nature of a mineral deposit embedded in the soil comprising producing acoustic waves at a point near said deposit varying at intervals the intensity of such waves, receiving at another point the direct acoustic waves travelling from said first point to said second 65

point and also the acoustic waves reflected from said deposit, converting said acoustic waves into electric oscillations and amplifying and recording same.

4. The method of ascertaining the position and nature of a mineral deposit embedded in the soil comprising producing acoustic waves at a point near said deposit varying at intervals the intensity of such waves, receiving at a plurality of other points the direct acoustic waves travelling from said first point to said second points and also the acoustic waves reflected from said deposit and electrically recording both said kinds of waves.

In testimony whereof I affix my signature.

JOHANN G. KOENIGSBERGER.
